UNITED STATES PATENT OFFICE.

CONSTANTINE G. MILLER, OF CHICAGO, ILLINOIS, ASSIGNOR TO MEAKER GALVANIZING CO., OF CHICAGO, ILLINOIS, A CORPORATION OF ILLINOIS.

ELECTROLYTIC GALVANIZING-MACHINE.

1,321,936.

Specification of Letters Patent. Patented Nov. 18, 1919.

Application filed January 19, 1917. Serial No. 143,361.

To all whom it may concern:

Be it known that I, CONSTANTINE G. MILLER, a citizen of the United States, and a resident of the city of Chicago, in the 5 county of Cook and State of Illinois, have invented certain new and useful Improvements in Electrolytic Galvanizing-Machines; and I do hereby declare that the following is a full, clear, and exact description of the 10 same, reference being had to the accompanying drawings, and to the numerals of reference marked thereon, which form a part of this specification.

This invention relates to an electrolytic 15 machine for electro-plating articles by passage of the articles through an electrolytic solution, and with the articles themselves functioning as cathode or negative poles, and with the anode or positive pole members 20 so disposed relative each article that any desired disposition of metal on the article takes place on all sides, both on the interior and exterior thereof. This machine is particularly designed for the handling of metal 25 drums, barrels or cylindrical objects, which it is desired to galvanize both on the interior and exterior surfaces. Heretofore, great difficulty has been experienced in effecting 30 galvanization of barrels or drums and similar cylindrical articles in a single process, to properly galvanize the same both on the interior and exterior surfaces. This machine, however, contemplates the automatic handling and passage of the objects through 35 an electrolytic solution, and with the anodes so disposed as to insure complete galvanization of the article on all its surfaces, both the interior and exterior thereof.

It is an object therefore of this invention 40 to construct a galvanizing machine constructed to handle cylindrical articles such as drums, barrels, or similar objects, and during passage thereof through the machine, insuring complete galvanization of 45 all surfaces both on the interior and exterior thereof.

It is also an object of this invention to 50 construct an electrolytic machine for galvanizing articles wherein movable anode members are provided, one for association with each article, and with movable means for making the article a cathode, together with other stationary anode members, so

that during the progression of the article through the machine, complete galvanization thereof is assured. 55

It is also an object of this invention to construct a galvanizing machine provided with a conveying mechanism for the movement of articles therethrough whereby the 60 articles are in themselves made cathodes in the machine, and with certain stationary anodes in the field of movement of the articles, and other movable anodes movable with the articles through the machine to permit 65 galvanization of all surfaces of the articles, and the different surfaces with different thicknesses of deposit where so desired.

It is also an object of this invention to construct a galvanizing machine into which 70 articles are introduced successively by feeding mechanism provided for the purpose, and with an anode member associated with each article for movement therewith through the machine, together with means for electrical connection to the article after introduction into the machine to make the article 75 a cathode member, to cause an electrolytic action to take place for disposition of the anode material upon the article and after 80 movement of the article through the machine with means operating to break the electrical circuit to the article, and transfer the article from the electrolytic solution through a rinsing bath to a point of discharge. 85

It is furthermore an important object of this invention to construct a galvanizing machine wherein articles are positively moved through the machine partially submerged in electrolyte and associated with 90 movable anode members moving with the article, and moving through the field of, and adjacent to stationary anode members, connected in an electrical circuit whereby the articles themselves are cathode members 95 to insure a rapid and complete galvanization of the articles during their progress through the machine.

It is also an object of this invention to feed 100 articles automatically into a galvanizing machine, passing the articles through a galvanizing solution in view of an operator, elevating the articles to drain the same and rinsing the articles before discharge, with the elements of the machine adjustable for 105 articles of different size and with the gal-

vanizing deposit on all or different parts of the article under the control of the operator at all times.

It is a further object of this invention to construct a galvanizing machine operating to effect an electrolytic deposit upon articles passed through the machine, insuring complete galvanization of all surfaces, both interior and exterior of the articles.

10 Other and further objects of this invention will be apparent by the disclosure in the drawings and specification.

The invention (in a preferred form) is illustrated in the drawings and hereinafter 15 more fully described.

On the drawings:

Figure 1 is a top plan view of a machine embodying the principles of my invention, with parts omitted.

20 Fig. 2 is a detail section on line 2—2 of Fig. 1.

Fig. 3 is a transverse section through the machine, with parts omitted and parts shown in elevation.

25 Fig. 4 is a fragmentary end view of one of the anode members.

Fig. 5 is a fragmentary top plan view thereof.

30 Fig. 6 is a side elevation of the machine at the discharge end thereof.

Fig. 7 is a fragmentary plan view of the lower portion of the machine.

35 Fig. 8 is a sectional view showing parts of the machine in side elevation at the entrance end thereof.

Fig. 9 is a fragmentary sectional view showing in side elevation one of the contact brushes which slides upon the flexible copper belt.

40 Fig. 10 is a fragmentary sectional detail on line 10—10 of Fig. 9.

Fig. 11 is a detail top plan view of a portion of the mechanisms of Fig. 9.

45 Fig. 12 is a detail view illustrating the bevel gear drive for mechanisms at one end of the machine.

Fig. 13 is a detail view taken on line 13—13 of Fig. 7.

50 Fig. 14 is a sectional detail view of a trip lever mechanism at one end of the machine.

Fig. 15 is a fragmentary end view of the feeding mechanism at one end of the machine.

55 Fig. 16 is a detail section on line 16—16 of Fig. 15, with parts omitted and parts shown in elevation.

Fig. 17 is an elevational view with parts in section of one of the anode carrying bars 60 on the continuous chain of the machine.

Fig. 18 is a fragmentary detail section on line 18—18 of Fig. 17.

As shown on the drawings:

The machine comprises in fact, two dupli-

cate machines having common operating mechanisms and consists of a tank denoted as a whole by the reference numeral 1, with a double walled central partition 2, extending therethrough, as clearly shown in Fig. 3. Mounted near the front or entrance end of the machine upon the side walls of the tank 1, are uprights 3, and secured thereto are bearing boxes 4, in which a horizontal transverse shaft 5, is mounted. Mounted near the rear or discharge end of the machine upon similar uprights 6, shown in Fig. 6, is a transversely extending shaft 7. Mounted upon said shaft 7, are four large belt wheels 8, and similarly, mounted in alignment therewith upon the forward transverse shaft 5, are four other belt wheels 9. Trained about the respective belt wheels 8 and 9, are a series of flexible copper belts 10, although, of course, any other conductor material may be used, or any type of link belt, cable or chain for the purpose capable of conducting an electric current.

The rear shaft 7, is driven by a chain 11, as shown in Fig. 6, engaged on the sprocket wheel on the shaft 7, and said chain is trained around another sprocket wheel on a shaft 12, which is journaled transversely of the machine at the rear end thereof. The shaft 12, is provided on its outer end with a worm wheel 13, which is driven from a worm 14, on a short longitudinally journaled shaft 15, provided with tight and loose pulleys 16 and 17, respectively. Secured transversely to the uprights 3, at the forward end of the machine, are cross-beams 18 and 19, respectively, and similar cross-beams 18 and 19, are mounted upon the uprights 6, near the rear end of the machine. Supported on the cross-beams 18, and extending longitudinally of the machine, are a pair of outwardly directed channels 20, upon which, at spaced intervals, are mounted uprights 21, with cross-members 22, connecting the same, upon which in turn, are supported longitudinal upwardly directed channel track members 23, the extreme ends of which are curved downwardly, as shown in Figs. 6 and 8. Said channels 23, afford tracks for the upper run of a pair of continuous chains 24, and secured to certain links thereof, as shown in detail in Fig. 17, are yoke bracket members 26, for engagement with transversely extending rods or tubular bars 25. Journaled on each side of the middle portion of each of said rods 25, are brackets 27, each having a contact shoe 28, formed thereon, the forward end of which is longer than the rear end thereof, as clearly shown in Fig. 18.

Secured in each of the brackets 27, and extending outwardly and parallel to the bar or rod 25, is a conductor bar 29, shown as square in cross-section, and connected to

each of said conductor rods 29, and supported upon the rods 25, are pairs of anode elements, hereinafter described. Secured upon each side of each of the bars 25, are 5 brackets 30, as shown in detail in Figs. 4 and 5, and said brackets, as clearly shown, are provided with outwardly extending angled arms or bars 31, which are adjustably mounted, and journaled in the outer 10 ends of said arms are sharp edged wheels or rollers 32. A substantially circular ring 33, is formed integral with each bracket 30, or attached thereto in any suitable manner, and depends below the same and attached 15 around said rings 33, is a sheet 34, of the galvanizing metal or plating material used in the process.

Said chains 24, at the forward end of the machine, as they leave the guide tracks 23, 20 are led around large sprocket wheels 35, mounted upon a shaft 36, journaled in bearings secured upon the uprights 3. The chains leaving the sprocket wheels 35, are led around sprocket wheels 37, thence over 25 idler sprocket wheels 38, and downwardly beneath idler sprocket wheels 39, and at the point at which said chains leave the sprocket wheels 38, the shoes 28, of the brackets 27, on said bars 25, move onto supporting bus bars 40, which, at the forward 30 end of the machine, are curved upwardly, as denoted by the reference numeral 41, to receive the shoes thereon as the chains leave the sprocket wheels 38. All of said sprocket 35 wheels 37, 38 and 39, respectively, are mounted upon shafts which are journaled transversely of the machine in suitable bearings provided for the purpose. At the point at which the chains 24, are led around the 40 idler sprocket wheels 37, a curved guide or track 42, is provided, against which said rods or bars 25, contact, to retain said rods engaged in the yokes 26, of the chains.

The chains 24, leave the guides 40, at the 45 rear end of the machine, as shown in Fig. 6, leading beneath idler sprocket wheels 43, upwardly over sprocket wheels 44, and downwardly beneath sprocket wheels 45 and 46, respectively, said sprocket wheels 46, being secured upon the drive shaft 12, whereby a drive is imparted to the chains. The horizontal run of the chains beneath the 50 sprocket wheels 45 and 46, is disposed over a rinsing tank 47, and, of course, suitable guides are provided (not shown) to support the anode carrying bars 25, as the same are moved along by the lower run of the chain. The chains 24, lead upwardly from the sprocket wheels 46, around sprocket wheels 55 48, and thence around sprocket wheels 49, journaled at the rear end of the machine and from which the chains lead upwardly around sprocket wheels 50, mounted upon a shaft supported upon uprights 51, at the

rear end of the machine. The upper run of 65 the chains then leads forwardly to the guide tracks 23, previously described.

Referring to Fig. 3, it will be seen that within the tank 1, which is divided into two longitudinal tanks by the central partition 2, are mounted frame structures comprising uprights 52, of non-conductive material, and lower horizontal members 53, also of non-conducting material. Laid transversely across said horizontal members 53, and spaced longitudinally through the tank, are bus bars 54, which lead upwardly along the inner uprights 52, and are secured thereto, and at their upper ends are connected to the guiding bus bars 55, which are supported 70 longitudinally of the machine in insulating supports 56. Laid longitudinally upon said spaced bus bars 54, in staggered relation, are a plurality of anode bars 57, and disposed slightly thereabove are insulating 75 track members 58, upon which the articles, denoted by the reference numeral 59, are rolled along through the electrolytic solution contained in the tanks. The articles 80 59, supported upon the tracks 58, are contacted along a portion of their upper un-submerged surface thereof by the flexible contact copper belts 10, as clearly shown in 85 Figs. 3 and 8. Supported centrally and longitudinally of the machine between each of 90 the respective pairs of contact belts 10, are horizontal supporting bars 60, shown in detail in Fig. 9, mounted upon uprights 61, and said bars 60, are provided with brackets 62, spaced therealong, as shown in Fig. 11, 100 100 with a rectangular aperture therethrough and with rollers 63, on the interior of said aperture. An upright rectangular bar 64, extends slidably through the bracket 62, and is provided with a series of holes 65, therethrough, adapted to receive a pin engaged 105 through any one thereof to support said bar in the brackets at any desired height. Pivoted on the lower end of each of the bars 64, are relatively long contact shoes 66, and said 110 shoes rest upon the top surface of the lower runs of the contact belts 10. Heavy conductor wires 67, are connected to said shoes 66, and lead upwardly and are connected to the brackets 62, which are connected to 115 bus bars hereinafter described.

Mechanism is provided for feeding the cylindrical articles 59, into engaging position around the anode elements which are carried by the chains 24. For this purpose, 120 as shown in Figs. 1, 2 and 8, ways 68, are mounted at the forward end of the machine to receive a barrel or other cylindrical article 59, longitudinally thereon, and two of such ways are provided, alined with one 125 another, one for each side of the machine, inasmuch as the machine is of double construction.

Slidable between said ways 68, as shown clearly in Figs. 7 and 16, is a wedged shaped pusher or thrust block 69. Mounted beneath said ways 68, are sprocket wheels 70, and 71, respectively, around which is trained a chain 72, provided with a stop or lug 73, on one link thereof, which serves to engage behind a lug 74, beneath the wedge block 69, to retract the same to position at the outer 10 end of the ways. Said block 69, is held retracted at the outer end of the ways by a spring impelled latch pin 75, which engages behind a pin 76, of the wedge block, and tripping means is provided to retract the 15 latch pin at certain intervals. When the latch pin is retracted, the pusher block 69, is moved rapidly along between the ways 68, to thrust the barrel or other cylindrical object therealong, and this movement is imparted to the pusher block by means of a cable 77, connected to the block and led around idler sheaves 78, 79, 80 and 81, and at its ends is provided with a weight 82, which is movable vertically alongside of an 20 upright 3.

The trip mechanism for retracting the latch pin 75, consists of a crank or finger 83, shown in detail in Fig. 18, which is secured upon the end of a long shaft 84, extending 30 longitudinally beneath the ways 68. At the other end of said shaft 84, as shown in Fig. 15, a crank 85, is connected, which is connected by a link 86, to a crank 87, and said crank 87, is secured upon a shaft 88, to 35 which another long crank or finger 89, is also secured and so positioned as to be contracted by one of the anode cross-bars 25, as it is thrust along on its guides 42, by the chains 24. The chain 72, upon which the 40 stop 73, is secured for retracting the pusher block 69, is driven continuously by the sprocket wheel 70, which is mounted upon a shaft 90, and secured upon said shaft 90, for the purpose, as shown in dotted lines in Fig. 45 7, is a bevel pinion 91, meshing with a bevel pinion 92, secured upon a long shaft 93. Also secured upon said shaft 93, is a pinion 94, meshing with a gear 95, and said gear 95, is secured upon a short shaft 96, together 50 with a small sprocket wheel 97, as shown in detail in Fig. 13. A chain 98, is trained around said small sprocket wheel 97, and also about a sprocket wheel 99, which is mounted on the same shaft with the sprocket 55 wheels 38. In view of the fact that the feeding mechanisms are in duplicate at the end of the machine, the shaft 93, as well as the shaft 88, serves for both feeding mechanisms, as shown in Fig. 7.

60 Referring to Fig. 1, it will be seen that a discharge mechanism is provided at the rear end of the machine, for ejecting the cylindrical articles after the same are passed out of the rinsing tanks 47, and for this purpose,

a pair of ways 100, are provided, one pair 65 for each side of the machine. The ways 100, are identical in construction with the ways 68, shown at the forward end of the machine, but with the wedge blocks operable outwardly or in an opposite direction and 70 with the mechanisms for actuating and releasing the same reversely mounted so that the pusher blocks may engage the inner edge of an article, and, when the pusher block is released, slide the article to the outer end 75 of the ways. Details of this discharge mechanism have not been shown for the reason that the construction is identical with that of the feed mechanism, except reversed, of course, for discharge instead of a feeding operation.

Mounted at one side of the machine is a motor generator set denoted as a whole by the reference numeral 101, and leading from the positive pole of the generator is a bus 85 bar 102, which is electrically connected to the bus bar 55. A series of bus bars 103, lead from the negative pole of the generator, and are connected transversely across the supporting beams 60, to the brackets 62, for 90 the cathode shoes or brushes 66.

The operation is as follows:

The articles or objects to be galvanized, which, in the present instance, are shown as cylinders which it is desired to galvanize 95 both on the interior and exterior surfaces, are rolled onto the ways 68, at the outer end thereof. Inasmuch as the chain 24, is continuously driven, an anode carrying bar 25, will be moved past the finger 89, shown in 100 Fig. 14, thereby actuating the system of levers to operate the release finger 83, shown in Fig. 15, for the latch pin 75. The pusher block 69, will then thrust the object 59, along on the ways 68, to the inner end thereof, and the mechanism is so timed that the article will be registered exactly over one of the anode elements, as clearly shown in Fig. 8. The chains 24, continuing their movement, the rollers 32, forming a part of one of the 110 anode elements, will contact the interior surface of the object 59, lifting the same upwardly from the ways and carrying the object over and into the tank, lowering the object down and onto the tracks 58. The 115 initial rolling movement is imparted to the object by contact of one of the rollers 32, with the interior surface thereof, but the object will finally move beneath the flexible copper contact belts 10, and when this occurs, the belts 10, which may be moving at a speed faster than the linear movement of the articles, may serve to roll the objects along on the tracks 58, and, due to contact with the article, establish the article as a 120 cathode pole in the electrolytic solution.

If the articles are rolled along by the flexible copper belts 10, instead of by the

rollers 32, the rollers 32, of the anode elements within the article will serve only to prevent the articles adjacent one another from contacting, that is, maintain the same 5 properly spaced during their progress through the machine. In actual practice, the rollers 32, will generally serve to positively move the articles through the machine. Although the copper belts 10, are 10 shown straight, they will generally flex or conform to the upper surface of the object with which they are in contact, thereby effecting a large frictional contact with the articles, and affording a good electrical connection therewith.

The anode metal sheet 34, on the interior of the object, may be of any metal desired to coat the interior surface of the article, and the outer stationary anode bars 57, over 20 and above which the articles are caused to roll, may be of the same or different metal. When the articles have been rolled to the rear end of the tank, as shown in Fig. 6, they pass outwardly from beneath the belts 25 10, and are carried by the rollers 32, along on the chain 24, upwardly out of the tank solution, thereby draining themselves. The articles are then conveyed downwardly into a rinsing tank 47, and are caused to roll for 30 a short distance therethrough on tracks 58, and are then elevated therefrom and carried to and deposited upon the discharge ways 100. Said discharge ways 100, are practically identical in construction with the feed 35 ways 68, and their associated mechanisms previously described, with the exception that the pusher blocks of the latter ways 100, operate to eject the cylindrical objects longitudinally outwardly out of registered 40 engagement with the anode elements. The entire operation of the machine is entirely visible to the operator at all times. The level of the electrolytic fluid in the tank is only sufficient to submerge the anodes 34, so 45 that approximately only two thirds of an object is immersed in the electrolytic fluid during the operation. It is obvious that according to the arrangement of the anodes and the control of the electric current used, 50 that any depth of plating of the objects may be attained, and the depth may be varied on the interior and exterior thereof, if so desired. In view of the fact that the anode elements are not positively attached to the 55 conveying chains 24, they may be readily removed therefrom either to reduce the number of anode elements in use, or to replace the same by anode elements of different material when desired.

60 I am aware that various details of construction may be varied through a wide range without departing from the principles of this invention, and I therefore do not purpose limiting the patent granted otherwise 65 than necessitated by the prior art.

I claim as my invention:

1. In a machine of the class described, a tank containing an electrolytic solution, means for supporting articles partially submerged in said tank, cathode mechanism 70 contacting the unsubmerged portion of the articles to cause movement thereof through the tank, and anodes movable with said articles through said tank.

2. In a machine of the class described, a 75 tank containing a solution of electrolyte, means for supporting articles for movement through the tank, continuous flexible copper cathode belts adapted to contact the exposed portion of articles partially submerged in the tank to cause movement thereof along on said means, and anodes in the tank composed of metal with which the articles are to be plated.

3. In a machine of the class described, a 85 tank of electrolytic solution, and movable anodes engaging and passing cylindrical objects thereinto and then disengaging the same to simultaneously permit the plating of the objects on both the interior and exterior surfaces thereof.

4. In a machine of the class described, a tank of electrolytic solution, means for supporting articles for movement therethrough partially submerged in said solution, electrical contact means for contact with the exposed portion of the articles adapted to move the same through said tank on said means, and pole members movable through the solution with said articles during movement thereof through the machine.

5. In a machine of the class described, a tank of electrolytic solution adapted to receive articles for movement therethrough partially submerged in said solution, a pole 105 member for contact with the unsubmerged portion of the articles during movement thereof through the machine, and pole members movable with the article through the machine.

6. In an electro-plating machine for plating articles on all surfaces thereof, pole members disposed within and on the exterior of the articles, and movable with the article during its progress through the machine.

7. In a machine of the class described adapted to receive articles moved continuously therethrough, movable pole members, one thereof contacting the articles, and both moving with the articles in their course through the machine, and stationary pole members mounted in the machine.

8. In a machine of the class described, a tank of electrolytic solution, a continuous conveyer, pole members associated therewith, feeding means to engage an article upon a pole member to be conveyed thereby into said tank, and an opposite pole member adapted to contact the article in the tank 125 130 135

- and to move the article independently of said first pole member through said tank during a plating operation.
9. In a machine of the class described, a tank of electrolytic solution, means supporting articles for movement through the tank while partially submerged therein, a flexible contact belt to contact the articles and forming one pole of the machine, and other pole members associated with the articles and out of contact therewith and movable with the articles in their progress through the machine.
10. In a machine of the class described, a tank of electrolytic solution, stationary means for supporting articles partially submerged therein, a pole member adapted to contact the unsubmerged portion of the articles to move the same along on said means through the tank, stationary pole members in said tank, and pole members movable along with the articles through said tank.
11. In a machine of the class described, a tank of electrolytic solution, supporting means for articles to be moved therethrough, a pole member adapted to contact the articles and to cause movement thereof through the tank, other pole members movable with the articles through the tank, feeding mechanism operating automatically to engage an article around a movable pole member, and discharge mechanism to eject the article out of engagement with its pole member after a plating operation on the article.
12. In a machine of the class described, a tank containing an electrolytic solution, stationary means for supporting articles in said tank, cathode mechanism contacting a portion of the articles to cause movement thereof through the tank, and anodes movable with said articles through said tank acting to maintain the articles spaced from one another.
13. In a machine of the class described, a tank containing a solution of electrolyte, means for supporting articles for movement through said tank, continuous flexible cathode means adapted to contact the exposed portion of articles partially submerged in the tank, and anodes in the tank composed of metal with which the articles are to be plated.
14. In a machine of the class described, a tank of electrolytic solution, and a plurality of means disposed within and on the exterior of cylindrical objects for rolling the same through the tank in spaced relation to simultaneously plate the objects both on the interior and exterior surfaces thereof.
15. In a machine of the class described, a tank of electrolytic solution, means for supporting articles for movement therethrough partially submerged in said solution, moving electrical contact means for contact with the articles to move with the same through said tank, and pole members movable through the solution and acting to move said articles through the machine.
16. In a machine of the class described, a tank of electrolytic solution adapted to receive articles for movement therethrough partially submerged in said solution, a moving pole member for contact with the unsubmerged portion of the articles during movement thereof through the machine, and pole members adapted to move the articles through the machine in spaced relation.
17. In an electro-plating machine for plating articles on all surfaces thereof, pole members disposed within and on the exterior of the articles, and movable to positively move the article through the machine.
18. In a machine of the class described adapted to receive articles moved continuously therethrough, pole members of opposite polarity movable through the machine, one thereof contacting the articles, and said members moving with the articles in their course through the machine, and stationary pole members mounted in the machine over which said articles are moved.
19. In a machine of the class described, a tank of electrolytic solution, a continuous conveyer, pole members associated therewith, and opposite pole members adapted to contact the article in the tank and to move with the article through said tank during a plating operation.
20. In a machine of the class described, a tank of electrolytic solution, means supporting articles for movement through the tank while partially submerged therein, a flexible contact belt to contact the articles and forming one pole of the machine, other pole members associated with the articles and out of contact therewith and movable with the articles in their progress through the machine, and means associated with said latter pole members to contact the articles and move the same through the machine.
21. In a machine of the class described, a tank of electrolytic solution, and movable anodes engaging the interior of an object to carry the object into the solution for a plating operation.
22. In an electro-plating machine for plating articles on all surfaces thereof, anode members engaging the interior of the articles and movable independently of the articles in their progress through the machine.
23. In an electro-plating machine the combination with a tank of electrolytic solution, of cathodes movable therein, and movable anodes engaging objects to carry the same into the solution to be conducted through the solution by said cathodes.
24. In an electro-plating machine the combination with a tank of electrolytic solution, of movable anodes adapted to engage

articles and carry them into the solution, and cathodes in said solution for conveying the articles through said solution, said anodes adapted to engage and carry the 5 articles out of the solution after their passage therethrough.

In testimony whereof I have hereunto

subscribed my name in the presence of two subscribing witnesses.

CONSTANTINE G. MILLER.
